UNITED STATES PATENT OFFICE.

HARRY THAYER KINGSBURY, OF KEENE, NEW HAMPSHIRE.

DESIGN FOR A TOY-CAR BLANK.

SPECIFICATION forming part of Design No. 34,328, dated April 2, 1901.

Application filed March 5, 1901. Serial No. 49,979. Term of patent 14 years.

To all whom it may concern:

Be it known that I, HARRY THAYER KINGSBURY, a citizen of the United States, residing at Keene, in the county of Cheshire, State of New Hampshire, have invented a certain new and original Design for Toy-Car Blanks, of which the following is a description, reference being had to the accompanying drawing, and to the letters of reference marked thereon.

- 10 My invention relates to a new and original design for a toy-car-body blank; and the invention consists in a blank for a toy-car body of the shape and configuration herein shown and described.
- 15 The invention is illustrated in the accompanying drawing, in which the figure is a plan view of a blank for a toy-car body embodying my design.
- In the drawing, A represents the blank as a whole, which, as herein shown, is cut out on two of its opposite sides to form the lugs or ears a, with round openings b, the lugs or ears C,

with slits d, and the central portion e. On its face, adjacent the edges, openings are provided. At the opposite ends of the blank the material is cut to form the recesses g h, having projecting tongues i, with the material of the blank practically unbroken between the ends of the tongues.

The leading feature of the design consists in the configuration of the opposite edges thereof.

Having thus described my invention, what I claim, and desire to secure by Letters Patent, is—

The design for a blank for a toy-car body, substantially as shown and described.

In testimony whereof I affix my signature in presence of two witnesses.

HARRY THAYER KINGSBURY.
